(57) **CLAIM**

An ornamental design for a mobile object, as shown and described.

DESCRIPTION

The file of this patent contains at least one drawing executed in color. Copies of this patent with color drawing(s)/photograph(s) will be provided by the Office upon request and payment of the necessary fee.

FIG. 1 is a right perspective view of a mobile object.

FIG. 2 is a front elevation view of the mobile object of FIG. 1.

FIG. 3 is a rear elevation view of the mobile object of FIG. 1.

FIG. 4 is a right elevation view of the mobile object of FIG. 1.

FIG. 5 is a left elevation view of the mobile object of FIG. 1.

FIG. 6 is a top plan view of the mobile object of FIG. 1; and, FIG. 7 is a bottom plan view of the mobile object of FIG. 1. In all figures, broken lines illustrate environmental structures and form no part of the claimed design.
